UNITED STATES PATENT OFFICE.

THOMAS B. FERGUSON, OF NEWARK, NEW JERSEY, ASSIGNOR TO FERGUSON FORGE
ENGINEERING CO., A CORPORATION OF NEW JERSEY.

OIL-BURNER.

1,384,943.

Specification of Letters Patent. Patented July 19, 1921.

Application filed December 6, 1919. Serial No. 342,944.

To all whom it may concern:

Be it known that I, THOMAS B. FERGUSON, a citizen of the United States, and a resident of Newark, county of Essex, and State of New Jersey, have invented certain new and useful Improvements in Oil-Burners, of which the following is a specification.

This invention relates to an improved burner for burning kerosene and similar oils, both light and heavy, and providing a burner that can be easily cleaned, that is, any carbon or dirt seated in the comparatively small outlet orifices can be cleaned without disturbing the efficiency of the heater or without shutting off the supply of fuel.

The invention is further designed to provide a burner in which the hot fuel, which has been vaporized by a vaporizing coil in passing through the nozzle, subjects an interior nozzle or inside nozzle to the action of its heat and thus maintains the pulverizing agent or vaporizing agent, such as steam or air, which passes through such inner nozzle, so that there is a preliminary gasifying or vaporizing which increases the efficiency of the burner.

The invention is further designed to provide a burner of this kind in which the parts are disposed so that the flame will not be extinguished by reason of being blown out or what might be termed "sucked out," thus insuring constant ignition of the gaseous mixture which is projected from the nozzle.

The invention is illustrated in the accompanying drawing, in which Figure 1 is a side view of my improved burner. Fig. 2 is a central vertical section of the apparatus shown in Fig. 1. Fig. 3 is an enlarged cross-section of the nozzle of the burner and its shield, taken on line 3-3 in Fig. 1, and Fig. 4 is an enlarged section of an improved oil filler used in connection with the burner.

The burner is illustrated as mounted on a plate 10, which is preferably inclined and at the forward end has the flat ignition plate 11, which is used for the reception of oil used in the preliminary ignition of the coils when the burner is to be started. The burner itself is preferably mounted so that it can be tilted slightly to adjust it to project the flame where desired, the burner sometimes being used where such change of direction is necessary, the burner being adapted for household use, such as in house heaters, also

for larger furnaces and for brazing outdoors and in other situations.

In the form shown, the bearings 12 receive the ear 13 of the nozzle, the bolt 14 acting as a pivot. The nozzle 15 is elongated in its preferred form, and is provided on the back with a fixture 16. The fixture 16 is screwed into the back of the nozzle and has a passage 17 which is fed by means of a pipe 18, which is connected with a vaporizing coil 19 which receives its supply from the oil feed pipe 20, which oil feed pipe is connected up, usually through a valved connection, with a suitable source of oil supply, which is not shown.

I prefer to cleanse the oil before it arrives at the vaporizing coil, and for this purpose I install a filter 21 which has a cylinder 22 in the casing 23, which cylinder has its upper end provided with a sieve 24, usually of wire cloth, the lower part of the cylinder providing a reservoir 25 into which sediment will settle, and it has a hand piece or thumb piece 26 by means of which it is inserted into and removed from the casing 27 of the filter. Side openings 28 in the cylinder permit the oil to flow into the cylinder, and it then passes out through the sieve 24. Any sediment being projected against the sieve finds its way to the bottom part of the cylinder and the filter only needs cleaning at intervals.

Within the main nozzle is an inner nozzle 28, which is preferably secured by screwing it in the end of the fixture 16, the inner nozzle and the main nozzle being spaced apart so as to provide an annular chamber 29, and the inner nozzle being elongated, it is subjected for the major portion of its length to the action of the hot oil vapor which passes through the chamber 29. The fixture is provided with a stuffing box 30, through which passes a stem 31, the stem 31 also passing through the inner nozzle and, being somewhat smaller than the inner nozzle, provides an annular space for the passage of steam, the stem having on its end a pin 32 which is adapted to be projected forward, when desired, to pass through the orifices of the inner and outer nozzles, these orifices 33 in the main nozzle and 34 in the inner nozzle being alined.

The rear end of the stem 31 is provided with means for manually operating the stem, in the form shown this consisting of a han-

dle 35 hinged to the back end of the stem and also hinged to a lug 36 which is secured to the ear 13 or other suitable support, and a quick forward movement of the handle 35 5 and its immediate withdrawal forces the pin 32 out through the orifices and quickly withdraws it again, thus keeping the orifices clear and cleaning them both at the same time. This does not interfere with the operation of the burner, and this cleaning takes 10 place at any time that it is desired to do so. Spaced from the nozzle, and surrounding it, is a shell 37, usually made in two parts and held together by screws 38 passing 15 through the ears on the two members of the shell, the shell permitting air to pass through it and mingle with the mixture coming out of the orifices 33, the shell 37 being spaced from the nozzle usually by separated 20 lugs on the inside of the shell, as will be clearly evident.

The front end of the shell has an opening 39, through which the mixture passes, the mixture then passing through the coil lining 25 40, the coil lining being inside of the coil 19 and the lining being preferably provided with suitable perforations 41. The coil 42 is also arranged around the coil lining 40, this coil being supplied by the feed pipe 43, 30 then extending, by means of the pipe 44, to a connection with the fixture, where it passes into the passage 45 which is in connection with the inside of the inner nozzle 28.

Suitably supported, and in the type shown 35 being supported on the forward end of the shell, is a shield 46 which is adjustable, this adjustment being usually provided by means of screws 47 or similar means, so that the shield 46 can be tilted to the proper angle, 40 and it is also spaced a slight distance transversely from the end of the shield so that air can pass through it to mingle with the flame. When the shield is tilted, so that its front 45 edge just touches the top edge of the jet projecting from the nozzle, it prevents the flame from being extinguished by reason of being blown out or "sucked out" through the force of the matter issuing from the nozzle.

50 When this burner is in operation the fuel passes through the nozzle and becomes ignited, is prevented from being blown out by the shield 46, and it heats the lining 40 of the coils 19 and 42, and while such lining is not essential, it is desirable, as when made of fire brick or similar heat resisting material, it becomes very hot, holds its heat, to some extent resists the action of the flame and acts to re-ignite the flame on any 55 temporary cessation, for any reason, of the flow of fuel. The hot steam passing through the pipe 44 and then into the inner nozzle is prevented from condensing to any appreciable extent by reason of the major portion 60 of the length of the inner nozzle being sur-

rounded by the hot fuel vapor passing through the main nozzle on its way to the orifices 33.

For the purpose of converting the burner to using a heavy oil I provide it with an 70 inlet 48, normally having a cap 49 thereon, this inlet 48 being used, in the case of heavy oil, for the purpose of feeding oil thereto. The pipe 20 is then used for conducting steam to the burner and the pipe 44 is used 75 for conducting air. This makes the burner easily adapted for the consumption of heavy oil, so that it can be used in many instances in conjunction with the heavier oils, but it is illustrated as being connected up for use 80 with the lighter oils.

I claim:

1. An oil burner comprising a nozzle with an orifice in the end and having means for supplying it with fluid fuel, said means including a vaporizing coil, an inside nozzle for steam, the nozzles having alined orifices, the major portion of the length of the inner nozzle being exposed to the action of the hot steam passing through the main 90 nozzle.

2. An oil burner comprising a nozzle, means for feeding fluid fuel to the nozzle, said means including a vaporizing coil in the path of a flame issuing from the nozzle, 95 an inner nozzle, each nozzle having an orifice, the orifices being alined, the inner nozzle having the major portion of its length exposed to the action of the hot fuel in the main nozzle, a stem passing through the 100 inner nozzle and having its rear end projecting so as to be manually manipulated, and a pin on the front end of the stem and adapted to be projected outwardly through both orifices.

3. An oil burner comprising an elongated nozzle, an elongated inner nozzle, the two nozzles being spaced apart to provide an annular chamber, a fitting in the rear of the nozzle having a passage therein communicating with the annular chamber, feeding means connected with the said passage, said feeding means including a vaporizing coil, said fitting having a passage for steam, and a feeding means for conducting steam 115 to the passage, said feeding means including a coil adjacent to the vaporizing coil, the major portion of the inner nozzle being exposed to the heat of the fuel in the chamber, each nozzle having an orifice, the orifices being substantially in line.

4. An oil burner comprising an elongated nozzle, an elongated inner nozzle, the two nozzles being spaced apart to provide an annular chamber, a fitting in the rear of 125 the nozzle having a passage therein communicating with the annular chamber, feeding means connected with the said passage, said feeding means including a vaporizing coil, said fitting having a passage for steam, 130

a feeding means for conducting steam to the passage, said feeding means including a coil adjacent to the vaporizing coil, the major portion of the inner nozzle being exposed 5 to the heat of the fuel in the chamber, each nozzle having an orifice, the orifices being substantially in line, and a coil lining within the vaporizing coil, said lining being made of material having fire resisting prop-
10 erties.

5. An oil burner comprising an elongated nozzle, an elongated inner nozzle, the two nozzles being spaced apart to provide an annular chamber, a fitting in the rear of 15 the nozzle having a passage therein communicating with the annular chamber, feeding means connected with the said passage, said feeding means including a vaporizing coil, said fitting having a passage for steam, a feeding means for conducting steam to the passage, said feeding means including a coil adjacent to the vaporizing coil, the major portion of the inner nozzle being exposed 20 to the heat of the fuel in the chamber, each nozzle having an orifice, the orifices being substantially in line, and a tapered coil lining around which the coils are arranged, 25 said lining being made of fire resisting ma-

terial and having perforations disposed over its surface.

6. An oil burner comprising an elongated nozzle, an elongated inner nozzle, the two nozzles being spaced apart to provide an annular chamber, a fitting in the rear of 30 the nozzle having a passage therein communicating with the annular chamber, feeding means connected with the said passage, said feeding means including a vaporizing coil, said fitting having a passage for steam, a feeding means for conducting steam to 40 the passage, said feeding means including a coil adjacent to the vaporizing coil, the major portion of the inner nozzle being exposed 45 to the heat of the fuel in the chamber, each nozzle having an orifice, the orifices being substantially in line, a stem passing through the fixture of the inner nozzle and having a pin on its forward end adapted to be projected outward through the aligned orifices, and means on the outer end of the 50 stem for manipulating it.

In testimony that I claim the foregoing, I have hereto set my hand, this 5th day of December, 1919.

THOMAS B. FERGUSON.
